United States Patent Office.

HENRY WIGLEY, OF NEW ALBANY, INDIANA.

Letters Patent No. 97,737, dated December 7, 1869.

IMPROVEMENT IN BOILER-FEED WATER-HEATERS.

The Schedule referred to in these Letters Patent and making part of the same.

To all whom it may concern:

Be it known that I, HENRY WIGLEY, of New Albany, in the county of Floyd, and in the State of Indiana, have invented certain new and useful Improvements in Heating and Purifying Water, &c.; and do hereby declare that the following is a full, clear, and exact description thereof, reference being had to the accompanying drawings, and to the letters of reference marked thereon.

The nature of my invention consists in the construction and arrangement of a device for heating and purifying water before it passes to the steam-boilers.

The great trouble with boilers is the danger of mud and sediment accumulating therein, which, in turn, causes the boiler easily to burn out. My invention will obviate the difficulty heretofore presenting itself in this respect.

In order to enable others skilled in the art to which my invention appertains, to make and use the same, I will now proceed to describe its construction and operation, referring to the annexed drawings, which form a part of this specification, and in which—

Figure 1 is a ground section;

Figure 2, a longitudinal vertical section; and

Figure 3, a vertical cross-section.

A represents a cylindrical reservoir, made of boiler-iron, its size to be governed by the number and size of the boilers, in connection with which it is to be used.

Inside of the reservoir A, is placed a smaller reservoir, B, of half-cylindrical form, open at the top, and extending from end to end of the outer reservoir.

The reservoir rests on perforated plates or supports C C at each end.

Along the upper edges of the inner reservoir B, extend flanges a a, which point downward, as shown in fig. 3, and on these flanges rests a perforated V-shaped cap, or cover, D, said cap extending the whole length of the reservoir.

A winding or tortuous pipe, E, leads from the outside of the outer reservoir A, through the cap D, into the inner reservoir B, opening at the rear end of the same.

The outer reservoir A is provided with several inlets and outlets—one, F, on the upper side, near the front end; one, G, on each side, about the centre; and one, H, about the centre of the bottom.

There is also an outlet, I, from the rear end of the

bottom of the inner reservoir B, which outlet passes through the outer reservoir A.

The object and uses of all these will be hereinafter fully explained.

The object of the apparatus being to cleanse and purify the water from the mud and sediment in it, so as to make steam without the mud and sediment getting into the boilers and caking therein, and rendering the boilers liable to burn out and explode; its practical operations depend, of course, on having the boilers first filled, and the machinery belonging thereto in operation, especially the "doctor," or pump that supplies the water. Then the fresh water from the "doctor," or pump enters, by pipe E, into the reservoir B, and the steam from a pipe connecting with the boilers enters by pipe F, and the action of the steam upon the water thus admitted settles the mud and sediment, and impurities of all kinds, in the bottom of the inner reservoir B.

In the meanwhile, the purified water is continually flowing into the boilers from pipes G G.

The pipe I is a valve attached to the inside of the bottom of the reservoir, and to which is attached a stop-cock, so that it can be opened whenever desired, and the mud and sediment accumulated in the reservoir by the action of the steam thereon will then be expelled from the reservoir. It is the peculiar shape of the reservoir which causes the water, by the action of the steam thereon, to precipitate the mud and sediment in the bottom.

The centre bottom-pipe H is to drain the outside shell or heater A.

Having thus fully described my invention,

What I claim as new, and desire to secure by Letters Patent, is—

1. A reservoir constructed as described, and connected with the boiler, substantially as herein set forth.

2. The combination of the outer reservoir A, inner reservoir B, provided with flanges a a, and V-shaped perforated cap D, tortuous pipe E, inlet F, and outlets G, H, and I, all substantially as herein set forth.

In testimony that I claim the foregoing invention, I have hereunto set my hand, this 8th day of January, 1869.

HENRY WIGLEY.
